UNITED STATES PATENT OFFICE.

FREDRICK H. AULD, OF COLUMBUS, OHIO.

INLAID WORK OF CURVED FORMATION AND METHOD OF PRODUCING THE SAME.

Application filed August 27, 1926. Serial No. 131,974.

This invention relates to improvements in an article of manufacture consisting in inlaid work of curved formation and of the method of producing the same.

5 The general object of my invention is to produce an inlaid article, such as a match box, a hair brush back, or a paper weight, comprising a bendable metal design-plate and a bendable wood veneer inlaid in the 10 recessed spaces bordering the tracery of the design, and to produce this article by a certain method by which the components of the article are respectively fabricated and treated and by which the veneer component 15 is made bendable and the several components united and inlaid one in the other and put into final curved form by a bending step.

The details which pertain to this article 20 and this method will more fully appear in the following specification.

In the accompanying drawings,

Figure 1 is a side elevation or edge view 25 of a strip of wood veneer.

Figure 2 is a plan view of a metal design plate with an illustrative design wrought thereon.

Figure 3 is an edge view of a sheet of celluloid which enters into the composition 30 of the article.

Figure 4 is a perspective view of a vessel containing a compound wood softening liquid.

Figure 5 is a plan view of a sheet of 35 wood veneer with the design plate under it, indicated by the dotted lines.

Figure 6 is a view of the inlaid product or article prior to the bending step.

Figure 7 is a vertical sectional view of one 40 form of bending die for performing the bending step in giving the final configuration to the article.

Figure 8 is a perspective view of the article preparatory to being united with a 45 suitable member to form, say a matchbox.

Figure 9 is a perspective view of the complete product attached to such member.

Figure 10 is a vertical sectional view of 50 another form of die for differently config-urating the product.

In building up my improved curved inlaid article I employ sheets of wood veneer one of which, in a raw state, is indicated by the numeral 1.

55 This veneer I immerse or otherwise treat with a liquid designed to soften the wood

and to enter its pores so as to maintain the wood in a submissive and pliable state whereby it may be bent or curved variously without cracking or breaking. The veneer 60 is then further treated to a bath of solvent liquid such as butanol.

I also fabricate on a metal plate, such as indicated at 2, a suitable design, either by the use of dies or by the well-known etching 65 process. When the plate is thus formed, it is coated with a solvent solution of camphor dissolved in a volatile solvent such as methanol.

In Figure 3 at the numeral 3 I have shown 70 the edge of a sheet of celluloid. This sheet is to be placed upon the design face of the metal plate next to the coating of solvent material so that the solvent will partially dissolve the celluloid to render the face of 75 the celluloid adjacent the design soft so that it will be gummy or sticky to constitute an adhesive to bind the celluloid to the plate and later to bind the veneer to the plate.

I next apply the veneer, treated in the 80 manner above described, to the celluloid sheet so that the now composite article consists of the design plate, the celluloid and the veneer. The latter having been coated with said solvent will partially dissolve the 85 adjacent side of the celluloid sheet and render this surface gummy or sticky for adhesive purposes.

What is here described appears in Figure 5 where the veneer 1 and the design plate 2 are shown one on the 90 other with the celluloid sheet between. This composite structure is placed in a suitable press, preferably one equipped with a heating device by which pressure may be applied upon the veneer to force it down into the 95 recesses bordering the tracery of the design, the heat of the press acting to further dissolve the celluloid and thus render it super- 100 ficially sticky by which the wood and the metal are intimately and permanently united. A pressure of about 1000 pounds per square inch is usually applied through a period of about ten minutes with the tem- 105 perature at about 115° C.

After this treatment the composite struc- 110 ture is removed from the press and the veneer is dressed off until the shattered parts that overlie the tracery of the design have been entirely removed and the tracery exposed through the remaining veneer which is now inlaid in the depressions about the tracery which is in relief.

2. As the metal plate is of a bendable character, and as the veneer has been rendered pliable, the next step is to bend both the plate and the veneer into the desired curvatures or configurations appropriate to the particular product. To this end I have shown in Figure 7 a die member 4 and a punch member 5, the former having a recess 6 corresponding in outline to the desired outline to be given the article and the latter having a projection 7 corresponding in shape to that of the cavity and of slightly less dimensions so as to give room for the composite article between the walls of the cavity and the projection. Pressure is then applied to the punch to bend the article from the flat position shown in dotted lines at *a* to the curved condition shown at *b* in full lines until the article finally assumes the form indicated in dotted lines at *c*. It has been found that by reason of the aforesaid treatment of the wood veneer it will bend and conform itself to the desired configuration without cracking or splitting.

3. In Figure 8 I have shown the completed article, generally indicated at 8, ready to be attached to any other suitable member, if any is needed, to build up a particular structure such as a match box, shown in Figure 9. The projecting tenons 9 form a convenient means of attaching the ornamental inlaid front of the box to the back designated 10. The bottom of the structure may be closed in any desired way in those cases where a bottom is required.

Thus it will be seen that I have produced an inlaid article composed, essentially, of a metal plate with a design in relief and of a wood veneer inlaid therein with the quality of bendability in the structure, the metal being bendable and the veneer rendered bendable without cracking or splitting in the manner stated.

It will further be understood that the method described results in practice in the production of this article.

It will be understood that I desire to comprehend within my invention, such modifications as may be necessary to adapt it to various conditions and uses.

Having thus fully described my invention, what I claim as new and desire to secure by Letters Patent, is:

1. An article of the character described consisting of a bendable metal plate having a design wrought on one face thereof, and a bendable wood veneer inlaid in the de-

pressions adjacent the tracery of the design, with the tracery exposed through the veneer, the plate and the veneer being fashioned into curved formations, the structure including an adhesive between the plate and the veneer, the said veneer having been treated to render it bendable.

2. An article of the character described, consisting of a bendable metal plate having on one face thereof a design with a tracery in relief and the surrounding surfaces depressed, and of a wood veneer inlaid in the depressions and removed at places over the tracery of the design, and an adhesive between the plate and the veneer to bind them together, the veneer being also bendable, and both plate and veneer being fashioned into curved contours, the said veneer having been treated to render it bendable.

3. The herein described method consisting in fabricating a design on one side of a bendable metal plate; in toughening and making pliable and bendable a veneer of wood by the application thereto of a softening liquid; in applying such veneer over the face of the design with an intervening adhesive; in subjecting this composite structure to pressure to inlay the veneer in the depressions about the design and shatter the portions over the tracery; in dressing off the face of the veneer to expose the tracery; and in subjecting this composite structure to a bending operation to give it a form characterized by curvatures.

4. The herein described method consisting in fabricating a design on the face of a bendable sheet of metal; in applying to the design face of the plate a celluloid solvent; in placing a sheet of celluloid on the design over the solvent coating; in subjecting a wood veneer to immersion in a bath to soften, toughen and make the wood pliable; in moistening it with a celluloid solvent; in applying such veneer upon the celluloid sheet; in subjecting the whole to pressure and heat whereby the celluloid is dissolved to form an adhesive and the wood and metal are united, the wood being thus inlaid in the design on the plate; in dressing off the surface of wood to expose the design; and in subjecting the composite structure to the bending action of dies by which to give the article a conformation characterized by curves.

In testimony whereof, I affix my signature.

FREDRICK H. AULD.
